CATHODE RAY TUBE

Leonard Francis Broadway, Ealing, London, and William Francis Tedham, Abbey Wood, London, England, assignors to Electric & Musical Industries Limited, Hayes, Middlesex, England, a company of Great Britain

Application March 29, 1935, Serial No. 13,660
In Great Britain March 26, 1934

2 Claims. (Cl. 250—27.5)

The present invention relates to improvements in cathode ray tubes.

A cathode ray tube is known which comprises a cathode, a modulating electrode, one or more auxiliary electrodes and an anode arranged within the tube in the order mentioned. The auxiliary electrodes and the anode co-operate in focusing the beam of electrons emitted from the cathode upon a screen, such as a fluorescent screen, associated with the tube. Frequently, the focusing electrodes are in the form of tubes or cylinders, and two or more of them may be of equal cross-sectional areas. It is found in this case that in order to get a good focus of the ray it is essential that the several electrodes should be very accurately aligned within the tube.

Hitherto the electrodes have been mounted upon wires held in a pinch sealed into one end of the tube or upon wires sealed through the side walls of the tube. With such arrangements it has been found difficult to locate the electrodes accurately in their correct relative positions and, if the wires are thin or of unsuitable material, they tend to bend during the baking process necessary to drive occluded gas out of the electrodes and the envelope of the tube.

An object of the present invention is to provide an improved mounting for the electrodes which does not suffer from the above-mentioned disadvantages and which facilitates the assembly of the electrodes within the tube envelope.

A further object is to provide, in a cathode ray tube having an envelope comprising a plurality of electrodes fixed to a support within said envelope, a unitary self-supporting structure comprising at least two of said electrodes disposed co-axially one behind the other in predetermined spaced relationship, a plurality of rigid metal rods disposed longitudinally of and around the axis of said electrodes, and a clamp, said electrodes and said clamp being rigidly connected with all of said rods, and said clamp engaging said support.

Another object is to provide a rigid unitary electrode assembly for a cathode ray tube which can be assembled before attachment to the pinch or any other part of the envelope of the tube.

A still further object is to provide a rigid unitary electrode assembly for a cathode ray tube in which a plurality of electrodes are each rigidly connected with a plurality of metal rods and wherein no insulating distance-pieces are required on the rods between electrodes. It has been found that the difference in expansion coefficients between such insulating distance-pieces and metal electrode-supporting rods causes the loosening of an electrode assembly during the baking process, and that it is difficult to obtain a satisfactory insulating material which can be machined to form distance-pieces of accurate

length. Furthermore, errors in the length of such distance-pieces are cumulative.

The invention will be further described with reference to the example shown in the accompanying drawings, in which

Fig. 1 is a side elevation of part of a cathode ray tube, with the envelope in section,

Fig. 2 is an end elevation of the support collar,

Fig. 3 is an end elevation of an electrode mounting assembly,

Figs. 4, 5, and 6 are end elevations of parts shown in Fig. 3,

Fig. 7 is a side elevation of the part shown in Fig. 6,

Fig. 8 is an end elevation of a spacer ring.

The cathode ray tube comprises a glass envelope in the form of a tubular portion 10 flaring out into a frusto-conical portion not shown. Upon the inside of the base of the latter portion there is disposed a fluorescent screen.

The end of the tubular portion remote from the screen is provided with an inturned tubular foot 11 on the inner end of which is formed a pinch 12 in which are sealed conductors connecting with the various electrodes. These conductors are omitted from the drawings for the sake of clearness.

A cathode shield 14, an accelerator 15, a modulating electrode 16 and a first anode 17, are arranged co-axially with the cylindrical portion of the envelope 10. The cathode shield 14 is in the form of a cylinder having a transverse diaphragm provided with an aperture. A cathode heater and a cathode are supported from the pinch, and lie within the cylindrical cathode shield 14, close behind the diaphragm, hence they are not visible in the drawings. A second anode, which does not appear in the drawings, is in the form of silvering on the tube walls. The electrodes 14, 15, 16, and 17 are mounted upon three parallel rods 18, which are of nickel or of "Staybrite" steel and symmetrically distributed about the tube axis. These rods serve both to support and to align the electrodes mounted thereon, and they are fixed, by means of a clamping collar 19, to the cylindrical glass foot 11 sealed internally within the tube. The clamping collar 19 (Fig. 2) is made of nickel in three similar sections and is adapted to be clamped upon the glass foot by means of clamping screws. Each section has an arcuate central portion and a flange 20 projecting radially outward from each end. The flanges of each section are clamped to the adjacent end flanges of the neighbouring sections by pairs of screws 21 and nuts 22. The sections may be formed from flat strip material and at the centre of the arcuate portion of each section the strip material is bent radially outward and doubled back upon itself to form a central radially projecting flange 23. In the bending operation an aperture is formed

in each flange 23 to receive the end of one of the support rods 18.

Each screw of two of the pairs of screws is provided with a spacing washer 24, these washers serving to space apart the three sections of the collar correctly. The other pair of screws serves to tighten the collar on to the glass foot or on to suitable packing placed around the foot and these screws are provided with spring washers 25. 10 The foot may, of course, be other than cylindrical, and in order to facilitate the clamping of the collar upon the foot the collar may be made of corrugated sheet metal.

The rods also pass through holes in bosses 29 formed on three nickel spacer rings 26, 27, and 28. 15 Each spacer ring is provided at its centre with a circular aperture 30, (Fig. 8). The spacer rings are placed at any convenient distance from one another along the support rods and serve to hold 20 these rods parallel and at the correct distances apart.

The electrodes that are mounted upon the support rods are, in the present case, all in the form of cylinders and have the same diameter, so that 25 a description of a mounting of one of them applied to all of the others.

The cathode shield electrode 14 is mounted as a sliding fit in a flanged nickel collar 31 (Fig. 4) which in turn is mounted upon an insulating annular plate 32 of mica bearing three holes through which the support rods pass. The mica ring is shown in Fig. 5, and the assembled electrode mounting is shown in Fig. 3. The flange of the collar 31 carries three symmetrically disposed holes 33 corresponding to three similarly disposed holes 34 in the mica ring, and the collar and ring are fastened together by nickel rivets 35 passing through these holes. The diameter of the rivets 35 is slightly less than that of the holes 33 and 34 and the exact location of the collar relative to the ring is effected by three lugs 36 punched out of the flange and which fit into three notches 37 cut out of the inner edge of the mica ring.

45 The three holes in the mica ring through which the support rods pass have a diameter larger than that of the rods, and the holes are fitted with nickel eyelets 38 the internal bores of which have a diameter substantially equal to that of the rods. 50 Each eyelet is in the form of a short cylinder having two thin tongues 39 extending outwardly from opposite sides of the cylinder. The tongues are bent over, passed through two slots 40 cut in the mica ring, one on either side of an eyelet hole, and bent back so as to secure the eyelet firmly in its hole. Alternatively the eyelets may be riveted in their holes.

Thus the electrode and the flanged collar 31 are insulated from the eyelets 38 by the mica ring 32, and the flange of the collar may, if necessary, be cut away, as indicated at 41, so as to be well clear of the eyelets. The external diameter of the mica rings 32 may be equal to the internal diameter of the cylindrical portion of the envelope 10, so that the rings assist in locating the assembly centrally within the envelope.

70 The electrodes of the electron gun, that is to say in this example the cathode shield 14, the accelerator 15, the modulator 16, and the first anode 17 are all mounted in this manner upon separate collars and mica rings, the first anode, on account of its length, having two sets of col-

lars and rings. These electrodes and the spacer rings 26, 27 and 28 are threaded, in the proper sequence, upon the three support rods and are accurately spaced from one another. The spacer rings and the eyelets on the mica rings are then rigidly fixed to the rods for example by spot welding. The cathode and its heater having been mounted in the pinch, the rods are clamped by means of the collar 19 upon the foot 11 and the latter is sealed within the main part of the envelope 10 of the tube with the pinch and electrode assembly extending within the cylindrical portion of the envelope.

While in the embodiment described above the leads to the electrodes are all taken through the pinch, if desired, leads to one or more of the electrodes may be taken through the side walls of the envelope to the electrodes. Provision may also be made for maintaining the rods and spacer rings at earth or any other fixed potential. Alternatively some of the rods may serve as leads to some of the electrodes; in this case the appropriate eyelets must be connected electrically to these electrodes. Furthermore, electrodes of different diameters may be accommodated by 25 making the flanged collars of correspondingly different bores.

Since the supporting rods for the electrodes are of a substantial thickness of metal, no trouble is experienced in induction heating the metal parts and no distortion results from the heating since the parts are held rigidly by the spacer rings and electrode mounting rings and are substantially free from strain after assembly.

Many of the parts in the assembly are duplicated and can therefore be produced by mass production methods.

We claim:

1. In a cathode ray tube having an envelope containing an electron gun consisting, apart from a cathode and an anode, of a plurality of electrodes fixed to a support within said envelope, the arrangement of a unitary structure, comprising a plurality of rigid metal rods, a clamp and electrodes including at least a cathode shield, a modulator and an accelerator electrode, said rods disposed longitudinally of and around the axis of said electrodes spaced from said envelope, said electrodes and said clamp each rigidly connected with all of said rods, a rigid metal spacer ring rigidly fastened to said rods and spaced from said clamp and electrodes, and said clamp attached to said support.

2. In a cathode ray tube having an envelope containing an electron gun consisting, apart from a cathode and an anode, of a plurality of electrodes fixed to a support within said envelope, the arrangement of a unitary structure, comprising a plurality of rigid metal rods, a clamp and electrodes including at least a cathode shield, a modulator and an accelerator electrode, said rods disposed longitudinally of and around the axis of said electrodes spaced from said envelope, said electrodes and said clamp each rigidly connected with all of said rods, a rigid connection between at least one of said electrodes and all of said rods consisting in an apertured plate of insulating material rigidly connected to said rods and said electrode, and said clamp attached to said support.
